Application filed February 20, 1930. Serial No. 34,596. Term of patent 14 years.

To all whom it may concern:

Be it known that I, JOHN N. Fig. 1 is a front view, and Fig. 2 is a plan

view of an ophthalmic mounting, showing my new design.

A novel feature of my design resides in the ornamental effect produced by the particular shape of the joints of the temples on either side of the eye glass rims.

I claim:

The ornamental design for an ophthalmic mounting, substantially as shown and described.

JOHN N. NELSON.
